UNITED STATES PATENT OFFICE.

KANSAS U. WHITTED, OF TOPEKA, KANSAS.

TYPE.

No. 813,848.

Specification of Letters Patent.

Patented Feb. 27, 1906.

Application filed January 13, 1905. Serial No. 240,864.

To all whom it may concern:

Be it known that I, KANSAS U. WHITTED, a citizen of the United States of America, residing at Topeka, in the county of Shawnee 5 and State of Kansas, have invented a new and useful Improvement in Type, of which the following is a specification.

The invention relates to printing-type from which the impression is made either directly, 10 as where the type itself is inked, or indirectly, as where the stereotype or electrotype process is used. It is of especial advantage where the matter is set by machine, as by the linotype, and the printing done indirectly by 15 the stereotype or electrotype process.

In setting matter by the linotype, for example, the slugs are all of the same thickness and length unless, indeed, the machine be adjusted from time to time to cast slugs of different 20 thicknesses or lengths. The act of adjusting the machine is, however, at least a time-consuming operation. In setting display and ornamental matter, such as large 25 and ornamental capital initial letters, and in advertising matter where large numerals, cuts, or other strongly-contrasting matter is used, and in numberless other such cases if the machine has not been adjusted or cannot be conveniently adjusted to cast the shorter 30 slugs the slugs are indented, then cut off, and the larger letter, figure, ornament, cut, or the like is then inserted in full body-type in the space left by the part cut off. Again, in mortised and other irregular cuts much difficulty 35 is encountered and time consumed in justifying the several parts together.

The foregoing instances are illustrative merely; but they serve to show that whenever it is desired to set up any matter or matter 40 in any form other than of the point or length of slug to which the machine is adjusted either the machine must be readjusted or the slugs cut, and in either event separate bodies of type must be inserted.

Now the present invention has for its object the avoidance of the above difficulties as far as possible; to provide an improved type which may be used in connection with linotype matter for printing other than matter 50 of the point or length of slug or of other form than that to which the machine is adjusted; to provide an improvement of the kind set forth which is extremely economical in manufacture and use, simple, and efficient; to provide a separate type-face which may be used interchangeably upon different bases and

which is of such construction that the faces may be used interchangeably upon a single base and which at the same time is economical and simple in manufacture and use, 60 which is efficient, strong, durable, which requires no nice adjustment in use, which may be used on any ordinary base without any alteration of the latter; to provide a flanged type-face which may be simply laid upon the 65 base and held there firmly in the lock-up, and withal to provide a labor-saving device for use in the art.

To these ends the invention consists simply of a thin type-face adapted to rest upon 70 the body and having a flange adapted to extend downwardly and be clamped between the adjacent bodies, as hereinafter described.

It consists, further, of the combination of the type-body and the separate type-face 75 having a flange extending downwardly therefrom between contiguous bases which serve to clamp the flange and thereby hold the type-face firmly in position; and the invention consists, further, of the parts, improvements, and combinations particularly pointed out and claimed herein.

In the drawings accompanying and forming part of this specification and in the description thereof I illustrate the invention in 85 its preferred form and show the best mode of applying the principles thereof; but it is to be understood that the invention itself is not to be confined to these drawings and the description of the drawings, that it may be applied 90 to other uses, and that parts and combinations thereof as specifically claimed may be used in connection with other devices of similar general nature, and that I contemplate changes in form, proportion, material, arrangement, and the substitution of equivalent members without departing from the spirit of the invention.

Figure 1 is an enlarged view of the improvement in simple form comprising the thin type-face and the flange. Figs 2 and 3 are enlarged elevations. Fig. 4 shows a simple method of making the improvement by the electrotype process. Figs. 5 and 6 represent end and face views, respectively, of a short column of linotype-slugs without the improvement applied thereto, Fig. 5 being taken through 5' 5' of Fig. 6. Figs 7 and 8 correspond to Figs. 5 and 6, respectively, but with the improvement applied, Fig. 8 showing an additional slug to help clamp the flange. Fig. 9 is an end view of the column

through the body of Fig. 8. Fig. 10 is a side view of Fig. 8 from the right. Fig. 11 shows another application of the invention in which, the face being rather large, two flanges are used. Fig. 12 is an edge view simply to show the locations of the flanges at the opposite ends of the faces. Fig. 13 is a face view, and Fig. 14 is a side view, of a larger-sized cut or plate made in accordance with the principles of my invention.

Like numerals and letters of reference indicate like or corresponding parts throughout the several views.

Figs. 1 to 10, inclusive, show the type adapted to print the letter "T" made in accordance with my invention. The improvement A consists merely of the type-face 4, having the flange 3. The letter is, as usual, shown in relief and may be provided with a plate 1. The parts 1 and 2 may of course be a single piece of the same contour or they may be made separately and then secured together, as by soldering or other means. Flange 3 extends downward at right angles, so as to be adapted to be clamped between contiguous bases. A simple manner of making the improvement is shown in full outline in Fig. 4, in which the full outline represents an electrotype with a back of only sufficient thickness to answer the purposes required. The tailpiece 3' is bent down at right angles to form the flange 3. This gives a copper-type, which is strong and durable and easily made either in large or small quantities. Of course it may be cast or cut or molded or made in any other suitable manner.

6, 7, 8, 9, 10, and 11 are slugs constituting a column of linotype matter. The matter shown on slugs 6, 7, 8, and 9 is intended to line x x , so as to allow for the insertion of the large or ornamental capital letter "T." Now in the present state of the art these slugs 6, 7, 8, and 9 would be cut off at x x and a body-type "T" would be inserted in the place left; but with my invention I simply place the type-face "T" (shown enlarged in Figs. 1, 2, and 3) on the body of the slugs with the flange against the side of the slug 6. Then the blank slug 5 may be placed next to slug 6, and the flange is clamped between 5 and 6. A lead or sheet of paper 12 may compensate for the flange. Ordinarily in such a case as this the slug 5 would be a blank, as it immediately precedes the paragraph; but obviously it may have printing-matter thereon or may be the furniture used in locking up the form; but in any event on locking up the form it is plain that the face will be held firmly in place by reason of the flange.

60 In using my invention with the linotype matter I would make the face three points thick, that being the depth of the faces of the linotype-slugs at present, so that when the separate face is laid upon the blank portion 65 of the slug all matter would be of the same

height, and I would make the flange one-half point thick; but it is clear that these thicknesses may be varied to suit different conditions.

In Fig. 11 is illustrated the manner of setting advertising matter by the linotype, in connection with my improvement. 13, 14, 15, 16, 17, 18, 19, 20, 21, and 22 constitute part of a column of linotype-slugs. Slugs 13, 14, 19, 20, and 21 are blank. Slugs 15, 16, 75 and 18 are set with "per," "pair," and "\$2.00," respectively, in suitable positions to be within the circle to be afterward placed thereon, and slug 17 has "hoes" thereon, set indented far enough to allow for inserting the letter "S." Now, instead of cutting these slugs I simply lay on the blank portions of the slugs the large letter "S," made in accordance with my invention, and having the two flanges, and also the circle of like construction. The flanges are clamped between the adjacent bodies, as between 13 and 14 and between 20 and 21. The lock-up holds them all firmly in position, although the ordinary assembly of the bodies will hold them firm enough for such handling to which they are subjected before they are locked in the chase. Obviously more than two flanges may be used wherever necessary. It is also clear that such matter as a cut may be inserted in place of the letter "S" or in place of the circle and that other matter—such as cuts, enlarged letters, ornaments, logotype, or other desired matter made in accordance with my invention—may be placed on the blank portions of the slugs with the flanges extending down between the adjacent slugs.

In Figs. 13 and 14, 23 represents a base or body having feet 24, 24. The body may be used for various faces, the face being clamped in place by the flanges extending down between the base and the contiguous bodies.

Obviously the invention is equally applicable to the other various kinds of letters, figures, ornaments, rules, borders, and cuts. 110 Indeed, by the term "type," which I use in a comprehensive sense, I do not intend to limit myself merely to definite letters, figures, or characters, but to include all such devices by which the printing is done, including most 115 comprehensively ornaments, rules, borders, cuts, electrotypes, and the like.

It is apparent that in the use of my invention in connection with linotype matter the necessity of cutting the slugs or readjusting the machine is avoided in the class of work described, and, furthermore, that my improved flanged type-face may be used anywhere upon any blank body, and, furthermore, that its use does not involve any special 120 form or kind of body, but that it may be used in connection with any ordinary type-body.

In such processes as stereotyping and electrotyping there is but little strain or suction on the type-face. Hence one or very few 130

flanges will suffice to hold the face in position; but in printing direct from the original form care should be taken, especially with the faces of larger size, that enough flanges are provided to hold the faces in place, and to this end attention should be given to the style of press, the strain, and suction varying therewith.

5 The improved flanged type-faces may be made and designated in accordance with the point system. They may be made of metal or other suitable material.

What I claim is—

1. The combination with a form having linotype-slugs with blank portions thereon, of an associate flanged type-face, said type-face being adapted to rest upon the blank portion of the slugs with the flange extending downwardly and clamped between adjacent slugs, substantially as set forth.

10 2. The combination with the product of type-casting or line-casting machines having

bodies and faces and blank portions on the bodies, of an associate flanged type-face, said type-face being adapted to rest upon the blank portions with the flange extending downwardly and clamped between adjacent bodies, substantially as set forth.

15 3. The combination with two or more lines of type with blank portions, of an associate type comprising a thin type-face and a flange secured thereto, said type-face being adapted to rest upon the blank portions, and said flange being adapted to extend downwardly between contiguous lines of type so as to be held firmly in place in the lock-up, substantially as set forth.

20 In testimony whereof I have hereunto signed my name in the presence of subscribing witnesses.
